DISPENSER CARTONS

Thomas E. Marion, Baltimore, Md., assignor to Joseph Shapiro, Baltimore, Md.

Application September 4, 1957, Serial No. 681,976

3 Claims. (Cl. 221—63)

This invention relates to paper or cardboard cartons and it is more particularly concerned with such cartons which are adapted to contain a plurality of articles and which contains structural modifications in the carton to support the articles therein and at the same time permit the removal of the articles one at a time.

One of the objects of this invention is the provision of such a carton having dispensing features associated therewith to permit removal of the contents unit by unit while maintaining support for the contents as a whole.

Another object of the invention is the provision of such a carton and dispensing feature in which no additional materials or elements are needed apart from the carton itself.

A further object of the invention is the provision of such a dispensing carton which has particular application to paper cups.

A still further object of the invention is the provision of a dispensing carton of the type mentioned which is simple and easy to use and inexpensive to manufacture.

A still further object is the provision of such a dispensing carton the use of which does not require the violation of sanitary conditions under which the articles may be disposed in the carton.

These and other objects, advantages and features of the invention will be apparent from the following description considered conjunctively with the accompanying drawing.

In the drawing:

Fig. 1 is a perspective view of one embodiment of this invention applied to a carton of nested paper cups with the carton closed and the dispensing features in the non-operative position.

Fig. 2 is a view similar to Fig. 1 with the carton in the process of being opened and with the dispensing features in the operative position.

Fig. 3 is a side elevational view of the fully opened carton with the dispensing features in operative position, the carton being supported in its normal upright position for use as a dispenser.

Fig. 4 is a transverse section along the line 4—4 of Fig. 3 on a larger scale, with all except the lowermost cup of the stack removed.

Fig. 5 is a fragmentary section along the line 5—5 of Fig. 4.

Fig. 6 is a diagonal section of a fragmentary portion along the line 6—6 of Fig. 4.

Fig. 7 is a view similar to Fig. 4 with the bottom cup in a partially withdrawn position.

Fig. 8 is a perspective view of the top part of the carton in the partially open position for hanging.

Fig. 9 is an inside corner view in perspective of one of the holding elements showing in dotted lines the dead center point between its operative and non-operative positions.

2

Fig. 10 is a view similar to Fig. 1 of another embodiment of the invention.

Fig. 11 is a view similar to Fig. 9 with the carton in a partially opened position and the dispensing feature in operative position.

Fig. 12 is a view similar to Fig. 1 of a further embodiment of the invention.

Fig. 13 is a front elevational view, partly broken away, of the embodiment of Fig. 12 in operative position.

Fig. 14 is a transverse sectional view along the line 14—14 of Fig. 13 on an enlarged scale, with all except one of the cups removed.

Fig. 15 is a section along the line 15—15 of Fig. 14.

Fig. 16 is a view similar to Fig. 1 of a modified embodiment.

Fig. 17 is a view similar to Fig. 5 of the same modified embodiment.

Fig. 18 is a view similar to Fig. 6 of the same modified embodiment.

Referring with more particularity to the drawing in which like numerals designate like parts, the embodiment illustrated in Figs. 1 to 9 comprises an elongated tubular carton 21 having sidewalls 22, 23, 24, and 25; upper end flaps 26, 27, 28 and 29 as upper extensions

25 of the side walls; and lower ends flaps 30, 31, 32, and 33 as lower extensions of the side walls, respectively, these end flaps being folded and provided with interlocking means 34 in a conventional manner, as shown, to form closures. One of the upper end flaps 29 has an aperture 35 therein to permit hanging the carton from a nail 36 on a wall or other suitable support. The contents of the carton, such as the paper cups 37 with flexible rims 38, are stacked in nested relation, as illustrated, with the bottom of the stack projecting downwardly.

To facilitate gaining access to the cups, the fold lines 39, 40, 41 and 42 between the side walls and the bottom end flaps are perforated or scored, thereby permitting these flaps to be quickly, neatly and easily removed by simply tearing them off along these lines, as shown in Fig. 2.

At a point below the position of the rim of the lowermost cup of the stack, the carton is provided at each of its corners with perforated or otherwise severable lines and fold lines to permit a reversing of a portion of the corner edges. These lines consist of an uppermost perforated line 43 extending from the corner edge of the carton in each case to either side thereof in the adjacent walls. Vertical perforated lines 44 and 45 extend from the end of the upper perforated line 43 downwardly.

50 From the bottom of the lines 44 and 45 angular fold or scored lines 46 and 47, respectively, converge downwardly to a point 48 on the corner edge.

As a result of this construction the convex portion 49 delineated by these perforated and fold lines when pushed inwardly will reverse itself and become a concave, trough-like member projecting radially inward. This reversal of the portion 49 causes it to pass through a median or dead center position as shown by the dotted lines in Fig. 9, from which it snaps into its final operative position.

65 The resulting trough-shaped portion has a lowermost edge 50 and the perforated and folded lines are so proportioned that this edge 50 makes an obtuse angle with the side wall of the lowermost cup in the stack so that the weight of the stack coming in contact therewith will tend to keep the section in its inner operative position rather than to cam it upwardly and outwardly into a non-operative position. In this manner, the stack of cups is firmly supported under its own weight. However, since the cups individually have flexible edges, the lowermost cup can be removed while the stack as a whole is under

this support, simply by grasping the lowermost cup and pulling it down. The outer rim or lip edges 38 of the cup flex inwardly at these support points, as shown in Fig. 7, and hence the cups can be passed around while the stack as a whole remains supported thereby.

These reversible portions 49 may be provided at any convex area of a carton, irrespective of whether the convex area is formed by rectilinear or curvilinear parts. Also, any desired number of such portions may be used in any particular case, so long as the necessary support is provided for the stack of material. The sizes of these reversible portions may also be varied for any particular purposes.

The embodiment illustrated in Figs. 10 and 11 is substantially the same as that shown in Figs. 1 to 9, except that the tear lines 39, 40, 41 and 42 at the edges between the side walls and end flaps are dispensed with and, instead, a perforated tear line 51 is provided completely encircling the carton at a point between the bottom flaps and the reversible portions. Thus, the bottom of the carton can be quickly opened by simply grasping the portion 52 of the carton below the tear line and twisting it off as shown in Fig. 11, instead of opening the bottom flaps and tearing off each one separately.

In the embodiment illustrated in Figs. 12 to 15, the sections formed by the perforated and fold lines are disposed on the sidewalls of the carton between the corners, rather than at the corners. Two or more of these sections may be provided and each of them comprises a bottom fold line 53, a pair of vertical perforated lines 54 and 55 extending upwardly from the ends of the fold line 53, and stepped perforated horizontal lines 56, 56 and 57 joined by vertical perforated lines 58, 58 forming an upper tab portion 59 at the top of an otherwise rectangular section 60. By pushing the section and tab portion inwardly, they become disconnected from the wall of the carton along the perforated lines and hinged downwardly along the fold line 53 with the tab portion 59 reversed in the bottom position. This tab portion is disposed in a slit 61 below the fold line 53, the distance therebetween being less than the distance between the fold line and the perforated lines 56, 56 so as to cause the section 60 to assume a curved shape, as shown in Fig. 15, thereby forming an upwardly facing arched shoulder 62 in alignment with the underside of the cup rims, whereby the stack 37 as a whole can be supported by these shoulders and yet permit the lowermost cup of the stack to be removed as in the case of the previously described embodiments.

The embodiment of Figs. 16, 17 and 18 is the same as those of Figs. 1 to 11, except that the delineated areas 49 are made somewhat longer and provided with a horizontal fold line 63 at their top ends.

5 horizontal fold line 63 in spaced relation below the top perforated line 43. A medial vertical perforated line 64 is also provided between the lines 43 and 63 along the corner edge of the box. As a result of these added features, the outer edges of the portion 49 adjacent the lowermost cup of the stack is slipped over as shown in Fig. 18 to form flaps 65 and 66 to lie along the exterior surface of the cup and thus oppose any tendency of the section 49 to move back to its non-operative position.

10 Having thus described my invention, I claim:

1. A one-piece carton for a stack of nested conical paper cups, said cups having individually flexible rims, said carton comprising cardboard walls forming an elongated container for the cups, said walls having extensions therefrom forming a group of closure flaps at each of the ends of the container, the flaps at one end being presented as the top and the flaps at the other end being presented as the bottom of the carton, said walls having areas thereof delineated by perforated and fold lines, said areas being adapted to be separated from the remaining portions of the walls along the perforated lines and hinged inwardly along the fold lines to form abutments for supporting the stack as a whole at the bottom thereof against the pull of gravity but permitting the removal of the lowermost cup of the stack by a force greater than the pull of gravity, said delineated portions being also provided with fold lines and cut lines to form flap extensions at the outer extremities of the abutments to contact and lie along the exterior surface of the lowermost cup of the stack and oppose by such contact any tendency of the said portion to return to its non-operative position.
2. A one-piece carton as defined by claim 1 in which the delineated portions are each formed at a corner of the carton.
3. A one-piece carton as defined by claim 2 in which the delineated portions are each bounded by an upper perforated line across a corner of the carton, vertical perforated lines extending downwardly from the ends of the horizontal lines and converging angular fold lines extending downwardly and inwardly from the lower ends of the vertical lines.
